(57) CLAIM

The ornamental design for a cooking vessel exterior base plate as shown and described.

DESCRIPTION

FIG. 1 is a bottom perspective view of the new design for a cooking vessel exterior base plate in a first embodiment, shown in an environment of use;

FIG. 2 is a bottom perspective view of the cooking vessel exterior base plate;

FIG. 3 is a top view thereof;

FIG. 4 is a bottom view thereof;

FIG. 5 is a side view thereof;

FIG. 6 is a bottom perspective view of the new design for a cooking vessel exterior base plate in a second embodiment, shown in an environment of use;

FIG. 7 is a bottom perspective view of the cooking vessel exterior base plate;

FIG. 8 is a top view thereof;

FIG. 9 is a bottom view thereof; and,

FIG. 10 is a side view thereof.

The broken lines showing a cooking vessel in FIGS. 1 and 6 illustrate environment that forms no part of the claimed design.

1 Claim, 10 Drawing Sheets
